(57) CLAIM

The ornamental design for a tamper-evident bag seal, as shown and described.

DESCRIPTION

FIG. 1 is a perspective view of a tamper evident bag seal showing our new design;

FIG. 2 is a top plan view thereof;

FIG. 3 is bottom plan view thereof;

FIG. 4 is a cross-sectional view of FIG. 2 along line 4-4;

FIG. 5 is a perspective view of the tamper evident bag seal of FIG. 1 shown in a partially folded configuration;

FIG. 6 is another perspective view of the tamper evident bag seal of FIG. 5;

FIG. 7 is a front elevation view of the tamper evident bag seal in the configuration as shown in FIG. 5;
FIG. 8 is a rear elevation view of the tamper evident bag seal in the configuration as shown in FIG. 5;
FIG. 9 is a left side elevation view of the tamper evident bag seal in the configuration as shown in FIG. 5, the right side being a mirror image;
FIG. 10 is a top plan view of the tamper evident bag seal in the configuration as shown in FIG. 5;
FIG. 11 is bottom plan view of the tamper evident bag seal in the configuration as shown in FIG. 5;
FIG. 12 is another perspective view of the tamper evident bag seal of FIG. 1 shown as installed on a bag in a sealed configuration;
FIG. 13 is a front elevation view of the tamper evident bag seal in the configuration as shown in FIG. 12;
FIG. 14 is a rear elevation view of the tamper evident bag seal in the configuration as shown in FIG. 12;
FIG. 15 is a left side elevation view of the tamper evident bag seal in the configuration as shown in FIG. 12, the right side being a mirror image;
FIG. 16 is a top plan view of the tamper evident bag seal in the configuration as shown in FIG. 12;
FIG. 17 is another perspective view of the tamper evident bag seal of FIG. 12 shown as installed on a bag in an unsealed or tampered evident configuration;

FIG. 18 is a front elevation view of the tamper evident bag seal in the configuration as shown in FIG. 17;
FIG. 19 is a rear elevation view of the tamper evident bag seal in the configuration as shown in FIG. 17;
FIG. 20 is a left side elevation view of the tamper evident bag seal in the configuration as shown in FIG. 17, the right side being a mirror image;
FIG. 21 is a top plan view of the tamper evident bag seal in the configuration as shown in FIG. 17;
FIG. 22 is another perspective view of the tamper evident bag seal of FIG. 12 shown as installed on a bag in a partially unsealed or tampered evident configuration;
FIG. 23 is a perspective view of the tamper evident bag seal of FIG. 1 showing an alternate embodiment;
FIG. 24 is a top plan view thereof;
FIG. 25 is bottom plan view thereof;
FIG. 26 is a perspective view of the tamper evident bag seal of FIG. 1 showing an alternate embodiment;

FIG. 27 is a top plan view thereof; and,
FIG. 28 is bottom plan view thereof.
